(57) **ABSTRACT**

An apparatus, method and system for sensing parameters related to water and/or ice being dispensed from a dispensing station of a refrigerated appliance is disclosed. The dispensing system includes a sensing system positionable at the dispensing station at the point of dispensing for liquid and/or ice to sense a parameter related to dispensed water and/or ice and produce a sensing signal.

**APPARATUS, METHOD AND SYSTEM FOR
A DISPENSING SYSTEM OF A
REFRIGERATED APPLIANCE**

**CROSS-REFERENCE TO RELATED
APPLICATION**

This application is a division of U.S. patent application Ser. No. 12/477,517, filed on Jun. 3, 2009, entitled "APPARATUS, METHOD AND SYSTEM FOR A DISPENSING SYSTEM OF A REFRIGERATED APPLIANCE," the disclosure of which is hereby incorporated herein by reference in its entirety.

FIELD OF THE INVENTION

The present invention relates to sensing parameters related to dispensed water and/or ice from the dispensing system of a refrigerated appliance. More particularly, the present invention relates to an apparatus, method and system for sensing parameters relating to dispensed water and/or ice from a dispensing system of a refrigerated appliance.

BACKGROUND

Dispensing liquid and/or ice from an in-door dispenser or refrigerator is well-known. In fact, many existing refrigerators, whether in a home, business or on the showroom floor, have an in-door dispenser for dispensing water and/or ice. These in-door dispensers lack a sensing system for sensing parameters relating to water and/or ice at the outlet for liquid and/or ice dispensing points.

What is needed is an efficient and effective apparatus, method and system for sensing parameters relating to dispensed water and/or ice from the dispensing system of a refrigerated appliance.

Therefore, it is a primary object, feature or advantage of the present invention to improve over the state of the art.

It is a further object, feature, or advantage of the present invention to provide state of the art apparatuses, methods and systems for sensing parameters related to ice and/or water dispensing from the dispensing station of a refrigerated appliance.

Another object, feature, or advantage of the present invention is to provide a module attachable about the dispensing station of a refrigerated appliance to provide a sensing of parameters relating to dispensed water and/or ice from the dispensing station.

A still further object, feature or advantage of the present invention is to provide a sensing module adapted for removable mounting at the dispensing station of a refrigerated appliance wherein the module is aesthetically complementary to the dispensing station and/or the refrigerated appliance.

Yet another object, feature, or advantage of the present invention is to provide a sensing module for a dispensing station of a refrigerated appliance that is seamlessly integratable at the dispensing station.

A still further object, feature, or advantage of the present invention is to provide a sensing system for a dispensing station of a refrigerated appliance fix providing notification or warnings to an operator or user regarding sensed parameters relating to the water and/or ice being dispensed.

Yet another object, feature, or advantage of the present invention is to provide a sensing system for a dispensing station of a refrigerated appliance that monitors parameters

2

related to dispensed water and/or ice to provide diagnostics information regarding the refrigerated appliance, water, ice and/or the dispensing station.

These and/or other objects, features, or advantages of the present invention will become apparent. No single embodiment of the present invention need achieve all or any particular number of the foregoing objects, features or advantages.

BRIEF SUMMARY OF THE INVENTION

According to one aspect of the present invention a refrigerated appliance is disclosed. The refrigerated appliance includes a housing, a dispensing system at the housing having a dispensing station and a dispensing outlet positioned to dispense water and/or ice at the dispensing station. The refrigerated appliance also includes a sensing system at the dispensing system adapted to sense a parameter related to dispensed water and/or ice and produce a sensing signal.

According to another aspect of the present invention, a method of dispensing water and/or ice from a refrigerated appliance is disclosed. The method includes initiating dispensing of water and/or ice and sensing a parameter related to water and/or ice at or near the dispensing. In a preferred form, the method also includes monitoring the parameter to determine if the parameter meets a predetermined criteria.

According to another aspect of the present invention, a sensing system for use with a dispensing system of a refrigerated appliance is disclosed. The system includes a sensor adapted to sense a parameter related to water and/or ice dispensing from the refrigerated appliance and produce a sensing signal and a controller in operative communication with the sensor and adapted to process the sensing signal.

BRIEF DESCRIPTION OF THE DRAWINGS

FIG. 1A is a front elevation view of a refrigerated appliance with a dispensing system having a sensing system for water and/or ice dispensing according to an exemplary embodiment of the present invention.

FIG. 1B is an enlarged view of the dispensing system taken along line 1B-1B in FIG. 1A illustrating various operating components of the dispensing system according to one embodiment of the present invention.

FIG. 2A is a perspective view of a removable sensing module according to an exemplary embodiment of the present invention.

FIG. 2B is a front elevation view of the sensing module shown in FIG. 2A being mounted at the dispensing station of a refrigerated appliance according to an exemplary embodiment of the present invention.

FIG. 2C is a front elevation view of the removable sensing module mounted at the dispensing station of the refrigerated appliance shown in FIG. 2B according to an exemplary embodiment of the present invention.

FIG. 3A-3D are flow charts of a method of the present invention.

**DETAILED DESCRIPTION OF THE
PREFERRED EMBODIMENT**

The present invention is directed towards a sensing system for sensing parameters related to dispense water and/or ice from a dispensing system of a refrigerated appliance.

Apparatus

FIGS. 1-2C illustrate exemplary embodiments of the present invention. According to one embodiment of the

present invention. FIG. 1A illustrates a refrigerated appliance **10** according to an embodiment of the present invention. Refrigerated appliance **10** may include one or both of a refrigerated compartment and a freezer compartment. The refrigerated and/or freezer compartments are enclosed by one or more doors hingedly attached to a cabinet body. A dispensing station **12** is positioned at the body of the refrigerated appliance, and customarily in one of the doors. Dispensing station **12** could be positioned at the door, either on the exterior or interior of the refrigerated appliance **10**. The present invention is not limited to refrigerated appliances having a dispensing station as illustrated, but extends to all types of liquid dispensing units that have a dispensing station such as free standing, shelf or cabinet water dispensers. As is customary, dispensing station **12** may include an ice dispenser **14** and/or water dispenser **16** to provide dispensing of both liquid and ice from dispensing station **12**. Ice and liquid dispensing occurs at housing **13** of dispensing station **12**. Within housing **13** of dispensing station **12** is a dispensing area **18**. Dispensing area **18** provides a space concomitant with dispensing points where liquid and/or ice may be captured by a receptacle. Dispensing area **18** may be recessed into the door or protrude from the general plane of the door, and is defined generally by dispensing area walls **20**. Dispensing area walls **20** partially enclose liquid and/or ice dispensing from ice dispenser **14** and/or water dispenser **16** at dispensing station **12**. Dispensing station **12** includes a dispensing area face **22** having dispensing station controls **23** for operating, monitoring or controlling dispensing station **12**.

As best illustrated in FIG. 1B, illustrating an enlarged view of dispensing station **12** shown in FIG. 1A, dispensing station **12** also includes a sensing system **24** at dispensing station **12** adapted to sense a parameter related to dispensed water and/or ice from water dispenser **16** and/or ice dispenser **14**. The sensing system **24** is further adapted to produce a sensing signal based on the sensed parameter relating to dispensed water and/or ice. Preferably, one or more sensors may be positioned at points of dispensing for ice dispenser **14** and/or water dispenser **16**. Thus, one or more parameters relating to the dispensed ice and/or water may be detected using one or more sensors **26** positioned at points of dispensing for water dispenser **16** and/or ice dispenser **14**. Sensors **26** may include one or more types of sensors such as, but not limited to, a flow meter, a water quality meter, a spectral sensor, a temperature gauge, an optical fiber sensor, a motion sensor, a sonar sensor, a conductivity sensor, a capacitive sensor, an inductive sensor, an optical sensor, a light sensor, or a pH sensor. With one or more of the aforementioned sensors positioned at dispensing points for water and/or ice at dispensing station **12**, several parameters relating to the water or ice being dispensed may be monitored. For example, sensed parameters may include, but are not limited to, such parameters as quantity, quality, condition, presence or non-presence of certain substances, contamination, turbidity, temperature, chemical make-up, or physical make-up. Sensors **26** could be used to monitor water and/or ice consumption on a global or per user basis by using known information such as the flow rate for the ice and/or water per unit of time. Sensors **26** are configured to produce a sensing signal based on the parameters sensed from liquid and/or ice dispensing. The term "dispensing" is used to indicate that the water and/or ice has already been dispensed, and thus sensing is performed on the dispensed water outside and/or at the outlet of the dispensing line or conduit through which the water and/or ice is transported. A control system **34** is in operative communication with sens-

ing system **24**. The control system **34** and sensing system **24** may be configured to communicate with each other by wired or wireless connections. According to another aspect, sensors **26** at the outlet points for water and/or ice dispensing could be configured to wirelessly communicate sensed information to a control board at a location remote to the dispensing area. For example, in one aspect, the system could include as a single-piece unit a power source (e.g., battery) for powering in combination with a Wi-Fi transmitter having a control board that acquires the sensed signal and transmits it using the onboard Wi-Fi functionality of the transmitter. Control system **34** may be configured to record, store, compare, quantify, publish, and/or communicate sensing data locally or remotely. Remote communication of data to a receiving location, data store or processing station could occur using data telemetry means known in that art. Similarly, remote communications of instructions or data to control system **34** could occur using data telecommand means known in the art. In one aspect, sensing system **24** may be configured to transmit and receive wireless signals from other accessories, whether on the refrigerated appliance **10**, or another appliance or system having data telemetry means. In another aspect, sensing system **24** may be configured with a scanner, such as an RFID scanner, configured to read and inventory data available via RFID tags associated with things in and around the refrigerated appliance **10** (e.g., age or use sensitive perishable or non-perishable products or components). Sensors **26** may be configured to multiplex with control system **34** to perform any one or more of the aforementioned functions. Control system **34** may include one or more data stores for recording or storing sensing data. Control system **34** may also include a controller **36**. A controller **36**, which may be a programmable controller such as a programmable logic controller (PLC), is in operative communication with sensors **26** and data store **40**. In a preferred embodiment, control system **34** is in operative communication with user notification system **50**. Notification of a sensed parameter meeting a certain criteria determined by control system **34** may be communicated to user notification system **50** from control system **34**. User notification of the sensed parameter may be provided by at the dispensing station **12** via visible, audible, and/or tactile signals. For example, user notification system **50** at dispensing area face **22** of dispensing station **12** may include a light or display **52** for providing a visible signal for notifying the user, a sound generator such as loud speaker **54** for notifying the user using an audible signal, or a tactile signal generator such as tactile sensation source **56** for providing a tactile signal for notifying the user of the sensed parameter or information relating thereto. Display **52** may include, in addition to light signals, a textural display for notifying user of the sensed parameter relating to liquid and/or ice dispensed from dispensing station **12**. Dispensing station **12** preferably includes a user interface system **42** for receiving commands from a user via controls **44**. User interface system is in electrical communication with control system **34** whereby user input at controls **44** is communicated to control system **34** for controlling controller **36**, data store **40**, user notification system **50** and/or sensing system **24**. Control system **34**, user notification system **50**, user interface system **42** and sensing system **24** are in electrical communication with a power source **38**. The present invention contemplates the power source **38** may include the refrigerated appliance **10**, an electrochemical cell (i.e., an alkaline or rechargeable battery), a photovoltaic cell, or a power generator operated by water and/or ice dispensing. In the case where power source **38** is a photovoltaic cell, the

photovoltaic cell may be mounted externally for capturing ambient light and/or near an existing light source of refrigerated appliance 10 for capturing light emitted internally or externally from refrigerated appliance 10. The present invention further contemplates power source 38 being an inductive power source.

FIGS. 2A-C illustrate another embodiment of the present invention. FIG. 2A illustrates a sensing module 30 configured for removable mounting at the dispensing station of a refrigerated appliance. Module 30 is configured in height, width, depth dimensions to fit seamlessly (i.e., removably mounted) within the dispensing area of a dispensing station in any commercial refrigerated appliance such as illustrated in FIGS. 2B-C. Much like a picture frame, module 30 includes top, bottom and side walls that mate to dispensing area walls 20 of a dispensing station. Another embodiment of module 30 could include side walls connected to a top wall. Still another embodiment of module 30 could include adjustable sidewalls, top and/or bottom walls for accommodating varying size dispensing areas of a refrigerated appliance or other liquid dispenser. Another embodiment of module 30 could include a narrow rectangular (non-frame-like) body configured for removable mounting to one of the walls 20 at dispensing station within proximity to dispensing points for ice dispenser 14 and/or water dispenser 16. For example, module 30 in this form could be fit or adhered to the top or side wall 20 of dispensing station. To remain seated within dispensing area 18 of dispensing station 12, frame 32 of module 30 may include one or more attachments 28 for securing to dispensing area walls 20 of dispensing station 12. Module 30 may also be configured for receipt within the dispensing area 18 and remain attached to dispensing area using a compression or friction fit whereby module 30 fits sufficiently snug within dispensing area 18 of dispensing station 12 to retain module 30 at the dispensing station 12. In a preferred form, module 30 includes an exterior portion adapted to fit with a complementary portion of the dispensing station 12. Further, frame 32 of module 30 may include exterior portions that are configured cosmetically to match dispensing area face 22 of dispensing station 12 or other cosmetic or design features of the host appliance. Module 30 may include one or more faceplates for being adaptable to different brands, makes and models of refrigerated appliances. Configured into frame 32 of module 30 are many of the same operational components as discussed supra relating to the embodiment of the present invention shown in FIGS. 1 and 2. When module 30 is seated within dispensing area 18 of dispensing station 12, sensors 26 associated with sensing system 24 are positioned at dispensing points for ice dispenser 14 and/or water dispenser 16. As previously indicated, sensors 26 are configured to sense a parameter related to water and/or ice dispensing. The measured parameters are electrically communicated to control system 34 where controller 36 processes the information. Control system 34 is in electrical communication with user notification system 50 for alerting the user of the sensed parameter relating to ice and water dispensing. As noted previously, user notification system may include a visual display 52, loud speaker 54 or tactile sensation source 56 for alerting the user of the sensed parameter. User interface system 42 is in electrical communication with control system 34. Instructions or input to the system from a user may be provided at controls 44 of control system 34. In one aspect of the present invention, alkaline or rechargeable batteries may be used as power source for powering control system 34, sensing system 24, user notification system 50 and/or user interface system 42. Module 30 may also be

configured to receive AC power from refrigerated appliance 10 whereby wire connections associated with module 30 are connected to an electrical connection/tie-in within dispensing station 12 or associated with refrigerated appliance 10. Module 30 may also include a photovoltaic cell configured to convert ambient light sources into energy for use by module 30. A photovoltaic cell may also be positioned relative to an existing light source of the refrigerated appliance whereby light energy from the refrigerated appliance is used to power module 30. Module 30 may also include a power generator positioned at and operated by water and/or ice dispensing for providing electrical energy for operating module 30. Thus, module 30 may be attached to a refrigerated appliance for monitoring or sensing parameters related to water and/or ice being dispensed from ice dispenser 14 and/or water dispenser 16. As previously indicated, sensors 26 may be used to monitor one or more parameters associated with liquid and/or ice dispensing. Controller 36 of control system 34 may be used to process the sensed information to determine if it meets a certain criteria for alerting the user. Control system 34 may be also be configured to record or store the sensed information within data store 40 for later analysis and/or subsequent notification to the user. Thus, module 30 includes all the same functionalities and components of the dispensing station illustrated in FIGS. 1-2, but in a modulated form. Thus, module 30 may be retrofitted to any new or existing refrigerated appliance or liquid dispenser having a dispensing station where the ability to sense parameters related to water and ice dispensing are desired. Further, using parameters gleaned from monitoring water and/or ice dispensing, user notification may be given regarding the status of various components within the refrigerated appliance such as a water filter that is expired or an ice maker that is malfunctioning.

System

In another embodiment of the present invention a sensing system for use with a dispensing station of a refrigerated appliance or other liquid dispensing appliance is disclosed. In a preferred form, the sensing system of the present invention includes one or more sensors 26 adapted to sense a parameter related to water and/or ice dispensing from a dispensing station 12 of a refrigerated appliance 10. The sensor 26 is further adapted to produce a sensing signal. The sensing signal is communicated control system 34 in operative communication with the one or more sensors 26. The control system 34 is configured to process the sensing signal received from sensing system 34. A user notification system is in operative communication with the control system 34. The user notifications system 50 is configured to generate a user-perceivable notification signal in response to the sensing signal received from sensing system 24. Control system 34 may include one or more data stores 40 whereby sensing data received from control system 34 may be stored or recorded within the control system 34. Sensing signal received from sensing system 24 may be processed in real-time or by post processing procedures or protocol programmed within controller 36 of control system 34. Depending upon the operating parameters or criteria programmed into controller 36, sensed information may be processed in real-time or post processed and a subsequent electronic signal sent to the user notification system 50 for providing a user-perceivable notification signal, such as a visible, audible, or tactile signal. Notification devices at the user notification system 50 provide notification to the user of the sensed parameter using a light source, a sound source, a

tactile signal source or textual display source. Sensors **26** of sensing system **24** may be configured to monitor parameters relating to the liquid or ice being dispensed. For example, parameters such as quantity, quality, condition, presence, contamination, turbidity, temperature, chemical make-up, or physical make-up may be monitored and/or sensed. Appropriate sensors **26**, such as those listed *supra*, may be positioned at dispersion points for ice and/or water at the dispensing station **12** for monitoring a parameter relating to the ice and/or water being dispensed. In sensing system **24**, control system **34** user interface system **42** and user notification system **50** may be configured into a module **30** that is configured for being removably mounted at a dispensing area of a refrigerated appliance or liquid dispenser. The module **30** may include a fixed or adjustable frame **32** portion adapted for being removably affixed to a complementary portion of the dispensing area **18** of dispensing station **12**. One or more of the exterior portions of module **30** may be configured cosmetically to match complementary portions of dispensing station **12**. For example, various cosmetically arrayed faceplates may be configured to match the dispensing area face **22** of dispensing station **12**. A user may provide input to the sensing system by way of controls **44** at user interface **42**. Module **30** may be configured to receive power from a power source **38**. For example, the sensing system may include an on-board power source **38** such as rechargeable power source. Alternatively, the sensing system may be configured to receive power from the refrigerated appliance **10**, such as where the module **30** is electrically tied into a power source aboard the refrigerated appliance **10**. In the modulated form, the sensing system may be configured whereby the module **30** is rechargeable offline and when fully charged reinserted into the dispensing area **18** of dispensing station **12**. Furthermore, module **30** may include a power pack adapted for receipt within module **30** that may be removed for offline charging and reconnected to module **30** for powering operation of the module **30**.

Method

FIGS. 3A-D illustrate a method of the present invention. According to one method, a module **30** is seated within dispensing area **18** of dispensing station **12**. Or, in the case where refrigerated appliance **10** includes sensing system **24**, the operator in either case initiates dispersion of water and/or ice at dispensing station **12** of refrigerated appliance (step **60**). Liquid and/or ice being dispensed from ice dispenser **14** and/or water dispenser **16** is monitored by sensor **26** for sensing one or more parameters relating to water and/or ice being dispensed from ice dispenser **14** and/or water dispenser **16**. Sensor **26** senses parameters relating to the water and/or ice at or near the point of dispersion (see step **62**). Steps **64-68** illustrate sensed parameters of the liquid and/or ice being dispensed. Sensed parameters may include, but are not limited to, sensing physical make-up of ice and/or water being dispensed, sensing chemical make-up of ice or water being dispensed, sensing turbidity of ice and water being dispensed, or sensing quality of the ice or water being dispensed. Further sensed parameters include sensing for the presence of ice and/or water, sensing for contamination of the ice and/or water, or sensing the temperature of the ice and/or water being dispensed. Further methods of the present invention contemplate sensing other parameters gleanable or perceivable from monitoring or analyzing the liquid and/or ice being dispensed from ice dispenser **14** or water dispenser **16**. Sensing data from sensor **26** is communicated electronically from sensing system **24** to control

system **34**. A controller **36** within control system **34** manages sensed data (step **80**). Controller **36** operating under instruction from on-board code within the controller or code programmed into the controller remotely, manages the data provided from sensor **26**. Data management, as illustrated in steps **82-92**, includes recording or storing data in data store **40**. Further management of data may include publishing data to a local or remote source, including making data available by communicating data locally or remotely via a computer network to an enterprise database associated with the business or a service company associated with providing service for the refrigerated appliance. Other data management include comparing, contrasting or quantifying the data by real or post-time processing protocols. The control system **34** also manages the sensory data to determine if a user-perceivable signal should be generated (step **94**). Control system **34** may opt to process and manage sensory data internally without apprising the user, such as for example where sensory data is stored for post-processing purposes (step **96**). In the case where it is desirable to notify the user of the sensed data or information gleaned from processing the sensed data, a user notification signal such as a user-perceivable signal is given. Steps **98-104** illustrate various user-perceivable signals for alerting the user. These steps include generating a textual signal, generating a visual or visible signal, generating an audible signal, or generating a tactile signal. If no operator acknowledgement of the signal generated is required (step **106**) the control system **34** will cycle the signal (step **108**) based on the number of cycles programmed into controller **36**. If user acknowledgement of the signal is required, control system **34** aborts signal generation upon receipt of an instruction from a user at controls **44** of user interface system **42** acknowledging receipt or appreciation of the signal being provided (step **110**). Control system **34** may be configured to require attention or care depending upon the parameter sensed from the liquid or ice being dispensed. In the case where no attention or care is required (step **112**), control system **34** may be configured to record historically the sensed parameters for subsequent instruction and signal generation, or for deriving historical information about the liquid and/or ice being dispensed from the refrigerated appliance (step **114**). In the case where attention or care is required upon acknowledgement of a parameter sensed from liquid and/or ice dispersion, control system **34** may be configured to communicate sensory data to a maintenance professional (step **116**) to provide necessary services to the refrigerated appliance, the ice dispenser or liquid dispensing system of the refrigerated appliance (step **116**). In the case where the parameter sensed from the water or ice being dispensed relates to the quality of the liquid and/or ice such as where a foreign or unwanted chemical is identified within the water and/or ice, sensory data may be communicated to public works to notify them of such issues (step **118**). Control system **34** may also be configured to provide a user with additional instructions (step **120**) relating to the attention or care required given the parameter sensed from the liquid or water being dispensed. Further, control system **34** may be configured to communicate sensory data to the manufacturer of the refrigerated appliance (step **122**) to alert the manufacturer of any problems or concerns relating to the refrigerated appliance. For example, in the case where water quality is identified as being poor as a result of filter life having expired, the manufacturer may be notified that the refrigerator in need of a new filter and the user subsequently notified and/or provided instructions on how to order or obtain a new filter for the refrigerated appliance. In some

instances a system reset may be required (step 124), and if not, the system continues normal operation (step 126). Control system 34 may be configured to provide instructions or notification of a need for system reset (step 128) if the system reset is required. For example, in the case where the system identifies that the water quality is poor as a result of filter life having expired, the control system further identifies the need for a reset of a filter life counter associated with the system to know when to alert the user when the new filter expires. Upon receiving instruction and notification of the need to reset the system (step 128), the system continues normal operation (step 130) whereby sensor 26 monitors parameters relating to the water and/or ice being dispensed from ice dispenser 14 and/or water dispenser 16 of dispensing station 12.

The embodiments of the present invention have been set forth in the drawings and specification and although specific terms are employed, these are used in a generically descriptive sense only and are not used for the purposes of limitation. Changes in the formed proportion of parts, as well as in the substitution of equivalences are contemplated as circumstances may suggest or are rendered expedient without departing from the spirit and scope of the invention as further defined in the following claims.

What is claimed is:

1. A refrigerated appliance comprising:
a housing having a freezer compartment and a refrigerated compartment;
a dispensing system on an exterior of the housing and accessible from the exterior of the appliance by a user wherein the dispensing system dispenses ice and water from separate outlets and the dispensing system comprises: a dispensing station; an ice dispensing outlet positioned to dispense ice at the dispensing station; and a water dispensing outlet positioned to dispense water at the dispensing station;
a sensing system at the dispensing station that produces a sensing signal of a sensed water parameter of the water dispensed from the water dispensing outlet and related to the dispensed water and produces a sensing signal of a sensed ice parameter of the ice dispensed from the ice outlet and that is related to the dispensed ice; and wherein the sensing system senses the sensed water parameter: (1) outside the water dispensing outlet; or (2) at the water dispensing outlet through which the water is transported and wherein the sensing system senses the sensed ice parameter: (1) outside the ice dispensing outlet; or (2) at the ice dispensing outlet through which the ice is transported.

2. The refrigerated appliance of claim 1 further comprising:

- a control system in operative communication with the sensing system wherein the control system operates to do one of the following: receive both the sensing signal of the sensed water parameter and the sensing signal of the sensed ice parameter; process the sensing signal of the sensed water parameter and the sensing signal of the sensed ice parameter; generate a response to a received sensing signal; and record the received sensing signal; and wherein the dispensing system delivers water and ice to a receptacle when the receptacle is positioned below the water dispensing outlet and the separate ice dispensing outlet respectively.

3. The refrigerated appliance of claim 2 further comprising a user notification system in operative communication with the control system and adapted to generate a notifica-

tion signal in response to a control signal and wherein the dispensing system further comprises at least one sensor at each of the water dispensing outlet and the ice dispensing outlet.

4. The refrigerated appliance of claim 3, wherein the sensing system, the control system and the user notification system are integrated into a module removably affixed to a complementary portion of the dispensing station; and wherein the module comprises an attachment point adapted to removably affix to the complementary portion of the dispensing station to mount at the dispensing station and wherein the module comprises at least one exterior portion adapted to fit with the complementary portion of the dispensing station.
5. The refrigerated appliance of claim 4, wherein the module comprises a picture frame geometry having a faceplate adapted to seat flush against peripheral inner walls of the dispensing station to keep the water dispensing outlet and the ice dispensing outlet fully accessible.
6. The refrigerated appliance of claim 5, wherein the faceplate is removably attached to the picture frame geometry whereby the faceplate matching the complementary portion of the dispensing station may be selected.
7. The refrigerated appliance of claim 4, wherein the module further comprises a user control interface in operative communication with the control system for operating a plurality of the following: sensing system; a user notification system; control system; and a secondary system in operative communication with the module.
8. The refrigerated appliance of claim 4, wherein the module is in operative communication with an electric power source that electrically powers the module and wherein the power source for the module comprises at least one of: the refrigerated appliance; an electrochemical cell; a photovoltaic cell; a power generator operated by water dispensing or ice dispensing or both water and ice dispensing; inductive powering.
9. The refrigerated appliance of claim 8, wherein the photovoltaic cell is mounted:
locally at the module for capturing ambient light and/or exterior lighting associated with the dispensing system and the module; and/or
remotely at the dispensing station near a light source for capturing lighting associated with the dispensing station.
10. The refrigerated appliance of claim 3, wherein the notification signal comprises one or more signal chosen from the group consisting of: a visible signal; an audible signal; a tactile signal.
11. The refrigerated appliance of claim 3, wherein the user notification system providing the notification signal comprises at least one device chosen from the group consisting of: a light; a sound generator; a tactile signal generator; and a textual display.
12. The refrigerated appliance of claim 3, wherein the control system further comprises a data store in operative communication with the user notification system and the sensing system and adapted to store/record the sensing signal and wherein the control system is configured to communicate sensory data to a manufacturer of the refrigerated appliance to alert the manufacturer of any problems or concerns relating to the refrigerated appliance and wherein the sensing system, the control system and the user notification system are integrated into the dispensing system.
13. The refrigerated appliance of claim 1, wherein the sensed water parameter comprises a sensed water parameter

11

chosen from the group consisting of: water quantity; water quality; water condition; water contamination; water turbidity and user consumption over a period of time; and

wherein the sensed ice parameter comprises a sensed ice parameter chosen from the group consisting of: ice quality; ice condition; ice contamination; temperature; chemical make-up; physical make-up; and user consumption over a period of time and wherein the sensing system senses the sensed ice parameter and the sensed water parameter using at least one sensor chosen from the group consisting of: a flow meter; a water quality meter; a spectral sensor; a temperature gauge; an optical fiber sensor; a motion sensor; a sonar sensor; a conductivity sensor; a capacitive sensor;

an inductive sensor; an optical sensor; a light sensor; and a pH sensor.

14. The refrigerated appliance of claim 1, wherein the sensing system further comprises an RFID scanner configured to read and inventory data available via RFID tags associated with an item or items that include the RFID tags in and around the refrigerated appliance.

15. The refrigerated appliance of claim 14, wherein the item or items are age or use sensitive perishable or non-perishable products or components.

16. A refrigerated appliance comprising:
a refrigerated appliance housing defining a freezer compartment and a refrigerated compartment therein;
an ice and/or water dispensing system positioned on an exterior of the housing and accessible from the exterior of the appliance by a user wherein the dispensing system comprises: a dispensing station; a water dispensing outlet positioned to dispense water at the dispensing station; and an ice dispensing outlet positioned to dispense ice at the dispensing station; and
a sensing system for use with the dispensing system that senses (1) outside the water dispensing outlet and the ice dispensing outlet; or (2) at the water dispensing outlet through which the water is transported and at the ice dispensing outlet through which ice is transported and wherein the water dispensing outlet and the ice dispensing outlet are separate dispensing outlets and each of the water dispensing outlet and the ice dispensing outlet have a detectable intrinsic parameter that are detected near points of dispensing originating at the separate dispensing outlets for dispensing into a user's receptacle spaced within a dispensing receiving area of the dispensing system; and

wherein the dispensing system further comprises: a sensor at each of the points of dispensing of the separate dispensing outlet in the dispensing receiving area in sensing communication with the points of dispensing; a sensing signal of at least one of the detectable intrinsic parameters from the water dispensing and the ice dispensing acquired by the sensor at at least one point of dispensing upon initiation of dispensing by an operator at a dispensing station of the refrigerated appliance; and a controller adapted to process the sensing signal.

17. The refrigerated appliance of claim 16 further comprising: a control system in operative communication with the sensing system wherein the control system operates to do one of the following: receive the sensing signal; process the sensing signal; generate a response to the sensing signal; and/or record the sensing signal; and

12

a user notification system in operative communication with the control system and adapted to generate a notification signal in response to a control signal and wherein the dispensing system further comprises at least one sensor at each point of dispensing of the water dispensing outlet and the separate ice dispensing outlet; and

wherein the refrigerated appliance further comprises a water dispensing outlet and a separate ice dispensing outlet that deliver water and ice respectively to a receptacle receiving area of the dispensing system positioned below the water dispensing outlet and the separate ice dispensing outlet.

18. The refrigerated appliance of claim 17, wherein the sensing system further comprises an RFID scanner configured to read and inventory data available via RFID tags associated with an item or items that include the RFID tags in and around the refrigerated appliance and wherein the item or items are age or use sensitive perishable or non-perishable products or components.

19. A refrigerated appliance comprising:
a housing having a freezer compartment and a refrigerated compartment;

a dispensing system on the exterior of the housing and accessible from the exterior of the appliance by a user wherein the dispensing system comprises: a dispensing station; water dispensing outlet positioned to dispense water at the dispensing station; and an ice dispensing outlet positioned to dispense ice at the dispensing station; and

a sensing system at the dispensing station that senses: (1) outside the water dispensing outlet through which water dispensed and/or outside the ice dispensing outlet through which ice is dispensed or (2) at the water dispensing outlet and/or at the ice dispensing outlet and wherein the sensing system produces a sensing signal of a sensed parameter that is related to the dispensed ice and/or water; and

a control system in operative communication with the sensing system wherein the control system operates to do one of the following: receive the sensing signal; process the sensing signal; generate a response to the sensing signal; and/or record the sensing signal; and
a user notification system in operative communication with the control system and adapted to generate a notification signal in response to a control signal and wherein the dispensing system further comprises at least one sensor at each point of dispensing of the water dispensing outlet and the separate ice dispensing outlet; and

wherein the control system is configured to communicate sensory data to a manufacturer of the refrigerated appliance to alert the manufacturer of any problems or concerns relating to the refrigerated appliance and wherein the communicated sensory data is water quality and, when a water filter is identified as having expired by sensing the water quality, the manufacturer is notified that the refrigerated appliance is in need of a new filter and the user subsequently notified and/or provided instructions on how to order or obtain the new filter for the refrigerated appliance.
